UNITED STATES PATENT OFFICE.

DANIEL H. RICKERD, OF MUSCATINE, IOWA.

AIR-HEATING ATTACHMENT FOR STOVES.

SPECIFICATION forming part of Letters Patent No. 731,224, dated June 16, 1903.

Application filed November 17, 1902. Serial No. 131,647. (No model.)

To all whom it may concern:

Be it known that I, DANIEL H. RICKERD, of Muscatine, in the county of Muscatine and State of Iowa, have invented certain new and useful Improvements in Air-Heating Attachments for Stoves; and I hereby declare that the following is a full, clear, and exact description thereof, reference being had to the accompanying drawings, which form part of this specification.

This invention is an improvement in air-heating attachments for stoves and furnaces; and its object is to provide a simple device whereby part of the heat of the waste products of combustion escaping through stove-pipes may be recovered and utilized to heat air, which may be admitted directly into the room containing the pipe or conducted to another room or apartment to warm the same.

The invention may also be utilized either as an air heating and circulating apparatus within the room containing the stovepipe in which the heater is located or to heat air drawn from the exterior and admitted from the heater into the room with the stove or into another apartment.

The nature of the invention will be fully understood from the following description, in connection with the drawings, which illustrate a practical form thereof, and the claims concisely state the particular features and combinations of parts for which protection is desired.

In said drawings, Figure 1 is a side view of a stove and pipe and attached air-heating devices. Fig. 2 is an enlarged vertical section through the air-heating section of the pipe; and Fig. 3 is a transverse section on line 3, Fig. 2.

In said drawings, A designates an air-heating section of stovepipe which may be connected in the usual manner with other pipe-sections a, arranged to conduct the waste products of combustion from a stove or furnace to a flue or uptake. The section A is preferably cylindrical in form and has a free passage-way for the products of combustion, and its ends may be made so as to telescope in the usual manner with the adjacent pipe-sections a, as shown in the drawings. In one side of section A, however, is a large pocket B, which projects into the pipe and is sepa-

rated from the interior thereof by a thin metallic wall b, and said pocket projects outside the pipe, forming an exterior enlargement or protuberance B' thereon, which is closed at its ends by heads b', which are provided with collars b² b³, which are adapted to telescope with the ends of air-pipes C and D, the lower pipe C extending down to near the floor of the room or may be led to any point of the room desired, while the upper pipe D extends upward and may extend to any point in the room where it is desired to conduct and discharge the heated air.

In Fig. 1 pipe C terminates near the floor directly beneath the heater, and pipe D terminates above the heater near the ceiling. This arrangement will produce a quick and rapid circulation of air in the room and rapidly heat the cold air therein.

If desired, the upper pipe D may be extended, as indicated by dotted lines D' in Fig. 1, into an overhead room, and thus supply heated air thereto. Also the lower pipe C may extend out to the atmosphere through the wall of the house, as indicated by dotted lines C' in Fig. 1, thus introducing fresh air to the heater.

It will be noted that the apparatus may be readily used as described either for heating and circulating air within the room or for introducing and heating fresh air, and either use is within my invention. Also, if desired, two or more air-heating sections A could be arranged in one pipe, as is obvious and as indicated by dotted lines A' in Fig. 1, and such sections may be used "tandem" or independently.

The device is very simple, but effective. It does not require any expensive construction of pipe. It does not interfere with the proper draft of the stove, and it does not have any open joints through which soot, smoke, &c., might escape into the air-pipes or room, and it can be conveniently located at any desired points in the length of the smoke-pipe.

Having thus described my invention, what I therefore claim as new, and desire to secure by Letters Patent thereon, is—

1. A smoke-pipe air-heater, comprising a section of stovepipe provided with an inwardly-extending pocket in its side, and an exterior enlargement opposite the pocket

forming therewith an air-heating chamber, and apertures in the ends of the enlargement exterior to the pipe for the connection of air-pipes, substantially as described.

5 2. The herein-described smoke-pipe air-heater, comprising a section of smoke-pipe having an interior pocket and an exterior enlargement forming with the pocket an air-heating chamber; with air-inlet and air-outlet
10 pipes detachably connected to the opposite

ends of said enlargement exterior to the pipe-section, substantially as and for the purpose specified.

In testimony that I claim the foregoing as my own I affix my signature in presence of 15 two witnesses.

DANIEL H. RICKERD.

In presence of—
EDNA WALLACE,
N. ROSENBERGER.
